UNITED STATES PATENT OFFICE.

CHARLES F. BARNDT AND WALTER R. JOHNSTON, OF COLUMBUS, OHIO.

WIND-SHIELD.

No. 887,179.

Specification of Letters Patent.

Patented May 12, 1908.

Application filed April 26, 1907. Serial No. 370,510.

To all whom it may concern:

Be it known that we, CHARLES F. BARNDT and WALTER R. JOHNSTON, citizens of the United States, residing at Columbus, in the 5 county of Franklin and State of Ohio, have invented certain new and useful Improvements in Wind-Shields, of which the following is a specification.

Our invention relates to improvements in 10 wind shields, especially shields adapted for use on automobiles, and comprises a shield adapted to be divided and one part thereof positioned at the side of the other part, the supporting frame being formed to collapse; 15 it also comprises a frame having a collapsible portion which, when extended, maintains the portion of the divided shield in position, and when collapsed, is adapted to secure the portions of the divided shields firmly together to 20 prevent rattling or breakage thereof.

With these and other objects in contemplation, our invention comprises the further parts and their combinations which are hereinafter set forth in detail and embodied in the 25 claims.

In the drawings, which are hereto attached and hereby made a part of this specification, Figure 1 is a front view of the shield with both parts in their extended position; Fig. 2 30 shows the shield folded as viewed from the vehicle seat, and one of the supporting frames swung downwardly and secured to the folded shield; Fig. 3 is a perspective view of one of the supporting frames detached.

35 Referring to the drawings in which the same numerals indicate the same parts throughout, 1 is the dash portion of an automobile or other vehicle, to which is secured the sash 2 which forms the lower portion of 40 the wind shield; at each end of the sash 2 are frame pieces 3 and 4, which are formed with the deep channel 5 running lengthwise thereof. The sash 2 is secured to said side frames at 6 and 6^a. The side frame, as seen in Fig. 45 3, is made up of two portions, a lower portion 7 and an upper portion 8, hinged together at 9 so that the upper portion may be folded inwardly; the upper portion 8 contains the eye 10 through which is passed the set screw 11.

50 Both side frames are similarly constructed and the channel 5 therein is wide enough to accommodate side by side the sash 2 and a second sash 12, the latter being adapted to be moved laterally when positioned in the channelled guides or side frames 3 and 4 and then 55 permitted to drop, guided by the channel

walls, at the side of the lower sash 2. When in extended position, the upper sash rests upon the upper edge 13 of the lower sash in contact with the flange 14 provided on said 60 edge; the lower sash 2 contains the clip 15 thereon between which and the flange 14 said upper sash 12 is positioned and held thereby against lateral movement.

When the upper sash has been positioned 65 upon the lower as shown in Fig. 1, the set screw 11 is turned through the eye 10 and made to engage the sash 12 which positions the latter firmly within the channel. When it is desired to lower the shield, the set screw 70 11 is removed, the sash 12 is lifted slightly and then moved laterally within the channel, and then permitted to drop within the channel by the side of the lower sash; the upper portion 8 of the said frame or guide 3 is then 75 dropped inwardly on the hinge 9 into engagement with the upper faces of the sash portions 2 and 12, the channel walls embracing said sashes; the set screw 11 is then reinserted through the eye 10 and turned into the 80 screw plate 16 until the two sashes are firmly secured together, whereby a very snug and compact structure is provided which will prevent any rattling or breakage of the sashes. The side guides or frames are in this manner 85 adapted to be lowered, and therefore do not offer any obstruction to the sight of the operator when the shield is folded.

The description above given for the operation of the one of the side guides or supports 90 is of course applicable to the other, which is constructed to operate in an identical manner.

The wind shield is braced by the rods 17 and 18 secured near the upper side at 19 and 95 20 to the lower sash, and extending forwardly to the frame of the automobile or vehicle (not shown). Our construction enables the wind shield to be folded merely by giving the upper sash a slight lateral movement and then 100 permitting the same to drop vertically within the grooved or channelled guides; therefore it is adapted for use with vehicles that have very slight clearance between the dash and the lamps which are usually provided just in front of the shield, and which have very slight space for revolving or turning a portion of the shield on the inner side of the vehicle; it is also novel in the construction of the side guides or supports, which have channels of 105 sufficient width to accommodate the shield portions side by side, and when the upper

portion is positioned at the side of the lower portion, the latter being in its normal position, the side guides may be collapsed to engage the upper faces of the shield portions, 5 and are then secured thereto to maintain the latter firmly in their folded position. Therefore, we not only bind the shield portions firmly together by means of the collapsible side guides, but also remove all obstruction 10 to the sight of the operator, inasmuch as his line of vision would be above the upper face of the lower shield portion; a distinct objection to the shields now in use is therefore obviated by our construction, and all obstruction 15 to the sight is removed when the shield is folded.

Our improved wind shield is easily made and put in place upon the vehicle, and is readily manipulated into the extended or 20 folded position, is very secure, and contains no parts which can readily be put out of order in use.

Having described our invention, what we claim as new and desire to secure by Letters 25 Patent is:

A wind shield comprising a lower sash, bracing means supporting the same, a channel secured at each side of said sash and being

of greater width than the thickness of said sash, a channel member hinged upon the said 30 channel, an upwardly extending flange formed along the upper edge of said sash, a second sash adapted to be positioned upon said first sash and having its lower side in engagement with said flange and its ends positioned in said hinged channel, a set screw mounted in said hinged channel member and adapted to force said second sash into secure engagement with a wall of said hinged channel member, said second sash being adapted 35 to be moved laterally in said channel and lowered in said channel to the side of the first sash, said hinged channel member being adapted thereupon to be folded laterally to embrace the upper edges of said sashes, said 40 set screw being adapted to be inserted at the same point of said hinged channel member to force said sashes into secure engagement.

In testimony whereof we affix our signatures in the presence of two witnesses.

CHAS. F. BARNDT.
WALTER R. JOHNSTON.
